UNITED STATES PATENT OFFICE.

GEORGE RIFFLARD, OF NEW YORK, N. Y.

FRAME OR BODY FOR AEROPLANES AND OTHER STRUCTURES.

1,009,996.

Specification of Letters Patent. Patented Nov. 28, 1911.

Application filed January 30, 1911. Serial No. 605,359.

To all whom it may concern:

Be it known that I, GEORGE RIFFLARD, (whose post-office address is No. 262 West Fifty-fourth street, New York, N. Y.,) 5 citizen of France, residing at New York, in the county of New York and State of New York, have invented certain new and useful Improvements in Frames or Bodies for Aeroplanes and other Structures; and I do 10 hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in aeroplane frames, and 20 other skeleton constructions; and the said invention has reference, more particularly, to a novel, strong, durable and simple construction of the frame or body-portion of an aeroplane, or other skeleton structure.

25 The present invention has for its principal object to provide a novel form of frame or body for aeroplanes and other bodies, which is arranged and assembled, so as to provide a very high degree of strength and 30 rigidity, and at the same time avoids complexity of structure, whereby said frame or body may be made of a few and simply formed parts, which can be easily and quickly assembled.

35 A further object of the present invention is to provide a novel tie or truss connection for joining and bracing the main elements of the body or frame-like structure.

Other objects of the present invention not 40 at this time more particularly enumerated will be clearly understood from the following detailed description of the same.

With the various objects of the present invention in view, the same consists, primarily, in the novel construction of aeroplane frame or body, or other skeleton-structure, hereinafter set forth; and, the invention consists, furthermore, in the novel arrangements and combinations of the various 50 parts, as well as in the details of the con-

struction of the same, all of which will be more fully described in the following specification, and then finally embodied in the clauses of the claim which are appended to and which form an essential part of this 55 specification.

The invention is clearly illustrated in the accompanying drawings, in which:—

Figure 1 is a detail side elevation of a part of an aeroplane frame or body, illustrating the novel method of constructing the same and the assembling of its parts, showing one embodiment of the principles of the present invention; and Fig. 2 is a plan or top view of the same. Fig. 3 is a vertical 60 cross-section taken on line 3—3 in said Fig. 1, looking in the direction of the arrow *a*, this figure being drawn upon an enlarged scale. Fig. 4 is a detail face view of the 65 novel ties or truss connections employed in the construction of the aeroplane body or frame; Fig. 5 is a side edge view of the 70 same; and Fig. 6 is a large detail longitudinal section of one end of the tie or truss-connections.

75 Similar characters of reference are employed in all of the hereinabove described views, to indicate corresponding parts.

Referring now to the said drawings, the reference-character 1 indicates the complete 80 and novel construction of aeroplane frame or body made according to and embodying the principles of the present invention, the same comprising the chords 2, the stanchions 85 3, and the stretchers 4. The said chords 2 are preferably four in number and extend longitudinally the length of the frame or body of the aeroplane; and, the same forms, substantially, the back-bone of said frame or body. It is extremely important to maintain 90 the strength and rigidity of said chords 2, and to avoid any form of construction in combining them with the other elements of the aeroplane frame or body which would weaken the same. Heretofore, in constructing aeroplane frames or bodies, the said chords 2 have been weakened by boring holes therethrough, for bolts or other fastening means employed in assembling the parts of the frame. It is one 95 100

of the novel features of the present invention, and its most important object, to provide a means for assembling said chords 2 in a proper relation to the other elements 5 of the aeroplane frame or body, without weakening them by boring holes therein, or cutting away any portion thereof, or passing any fastening means through the body thereof. The said chords 2 form preferably 10 the longitudinal corners or edges of the complete frame or body. The chords 2, which are parallel in a vertical plane, are separated and supported in proper relation to each other, by means of a plurality of 15 suitably spaced or disposed stanchions 3, the ends of which abut the inner surfaces of said chords 2. The chords 2, which are parallel in a horizontal plane are separated and supported in proper relation to each 20 other, by means of a plurality of suitably spaced or disposed stretchers 4, the ends of which abut the inner surfaces of said chords 2. The means for assembling and retaining, in the proper relation one to the other, the 25 said chords 2, stanchions 3 and stretchers 4, comprises the following features:—There is provided a yoke-bolt 5, the same being formed ultimately with a U-shaped body, the free ends 6 of which are screw-threaded 30 to receive nuts 7. In connection with said yoke-bolt 5, there is provided a binder-plate 8 which is perforated so as to receive the screw-threaded ends 6 of said yoke-bolt 5. The ends of the stanchions 3 are provided 35 with suitable perforations for the reception of a part of said yoke-bolt 5, which passes transversely therethrough. A shank-portion 9 of said yoke-bolt 5 is then turned or bent so that it abuts the outer surface of one 40 of said chords 2, and presents one of the ends 6 in proper position to receive the one perforated end of said binder-plate 8 and a nut 7 for interlocking the said parts in such assembled relation. Another shank-portion 45 10 of said yoke-bolt 5 is then turned or bent so that the same will pass through suitable perforations with which the ends of said stretchers 4 are provided, the other of the said ends 6 projecting beyond the 50 outer surface of said stretcher 4 in proper position to receive the other perforated end of the binder-plate 8 and a nut 7 for interlocking said parts in such assembled relation. As thus arranged, the said yoke-bolt 5 and said binder-plate 8, together with the 55 nuts 7, serve to bind together in their assembled relation, the chords 2, the stanchions 3 and the stretchers 4, in a strong and permanent manner, without necessitating 60 the use of bolts, passing through said chords, or cutout portions of any kind to be made therein, whereby the structure would be weakened. The yoke-bolt 5 when thus assembled, in the manner above described, 65 presents a loop or anchor-portion 11 at the junction of each stretcher 4 and stanchion 3, the same providing an anchoring place for securing the ends of the interior cross-ties or truss-connections 12 which are a further aid to the rigidity and strength of the 70 whole frame or body 1. The said tie or truss-connections 12 comprise an anchor-plate 13, provided at one end with a perforated eye-portion 14, and at the other end with another perforated eye-portion 15, said eye-portion 14 being threaded upon one of 75 said loops or anchor-portions 11 formed by said yoke-bolt 5, as above described, while the other eye-portion 15 is adapted to receive one end of a tie-rod or wire 16, the 80 free end-portion of which is riveted over so as to form a retaining head 17. The other end of said tie-rod or wire 16 is provided with screw-threaded portion 18 which is received in a tightening nipple 19, said 85 nipples 19 being supported by a stirrup-like member 20 which is provided with a reinforcing plate 21, said stirrup-like member 20 and its reinforcing-plate 21 being perforated to permit the passage of 90 the shank of said nipple 19 therethrough, while retaining in held engagement the enlarged head 22 of said tightening nipple 19. Said stirrup-like member 20 is also provided with a rearwardly extending tail-piece 23 95 which is formed with a perforated eye-portion 24, the latter being threaded upon another of said loops or anchor-portions 11 of the yoke-bolts 5, and the same being preferably diagonally opposite to the loop or 100 anchor-portion 11 to which said anchor-plate 13 is connected. Said tie-rod or wire 16 may be tightened and rendered taut by taking up the slack of the same by screwing the same in said nipple 19 until the desired 105 tension is obtained. The said cross-ties or truss-connections 12 extend diagonally throughout the interior of the said frame or body 1, substantially in the manner shown in Fig. 3 of the drawings. Arranged in 110 connection with said yoke-bolts 5 are longitudinally extending ties or truss-connections 25, the details of the construction of which are the same as described in connection with said cross ties or truss-connections 115 12. The various eye-portions of said longitudinally extending ties or truss-connections 25 which lie in horizontal planes are threaded upon such portions of the yoke-bolts 5 which pass through the ends of said stanchions 3 and stretchers 4, said stretchers 4 being provided with cut-out portions or 120 grooves 26 to permit the passage outward from said yoke-bolts 5 of the various parts of said ties or truss-connections 25, the latter being adapted to stretch diagonally between said stretchers 4. In like manner, the various eye-portions of said longitudinally extending tie or truss-connections 25 which lie in vertical planes are threaded upon such 125 130

portions of the yoke-bolts 5 which pass through the ends of said stanchions 3, said stanchions being also provided with cutout portions or grooves 27 to permit the passage 5 outward from said yoke-bolts 5 of the various parts of said ties or truss-connections 25, the latter being adapted to stretch diagonally between said stanchions 3.

It will thus be understood, that the various stretchers 4 and stanchions 3 are firmly and securely tied or trussed against displacement from their interbound relation to said chords 2, whereby an exceedingly strong, durable, and efficient construction of 15 frame or body for aeroplanes, or other skeleton-structures, is provided.

I am fully aware that changes may be made in the arrangements and combinations of the various parts, as well as in the details of the construction of the same, without departing from the scope of my present invention as set forth in the foregoing specification and as defined in the appended claims. Hence, I do not limit my invention 25 to the exact arrangements and combinations of the parts as described in the said specification, nor do I confine myself to the exact details of the construction of the said parts as illustrated, in the accompanying drawings. 30

I claim:

1. A construction of aeroplane frames or bodies, or other skeleton structures, comprising chords, vertically disposed stanchions 35 between said chords, horizontally disposed stretchers between said chords, yoke-bolts, a portion of each yoke-bolt passing through adjacent ends of a stanchion and a stretcher as the same abut a chord, and a portion of 40 each yoke-bolt extending along the exterior of said chords, a binder-plate connected with each yoke-bolt, and nuts for securing said binder-plates in place, substantially as and for the purposes set forth.

2. A construction of aeroplane frames or bodies, or other skeleton structures, comprising chords, vertically disposed stanchions between said chords, horizontally disposed stretchers between said chords, yoke-bolts, a portion of each yoke-bolt passing through adjacent ends of a stanchion and a stretcher as the same abut a chord, and a portion of each yoke-bolt extending along the exterior of said chords, a binder-plate 55 connected with each yoke-bolt, nuts for securing said binder-plates in place, and a tying means extending diagonally from one yoke-bolt to another, substantially as and for the purposes set forth.

3. A construction of aeroplane frame or body, or other skeleton structure, comprising longitudinally extending chords, vertically disposed stanchions, the ends of which abut 60 said chords, horizontally disposed stretchers the ends of which abut said chords, yoke-bolts passing through the ends of said stanchions, each yoke-bolt having a shank-portion passing through the adjacent end of one of said stretchers and a shank-portion 65 extending along one exterior side of said

bolts passing through the ends of said stanchions, each yoke-bolt having a shank-portion passing through the adjacent end of one of said stretchers and a shank-portion extending along one exterior side of said 70 chords, a binder-plate connected with the ends of the shank-portions of each yoke-bolt and adapted to extend along another exterior side of said chords, and nuts for securing said binder-plates in place, substantially as and for the purposes set forth.

4. A construction of aeroplane frame or body, or other skeleton structure, comprising longitudinally extending chords, vertically disposed stanchions, the ends of which 80 abut said chords, horizontally disposed stretchers, the ends of which abut said chords, yoke-bolts passing through the ends of said stanchions, each yoke-bolt having a shank-portion passing through the adjacent 85 end of one of said stretchers and a shank portion extending along one exterior side of said chords, a binder-plate connected with the ends of the shank-portions of each yoke-bolt and adapted to extend along another exterior side of said chords, nuts for securing said binder-plates in place, and a plurality 90 of ties or truss-connections extending diagonally from one yoke-bolt to another, substantially as and for the purposes set forth.

5. A construction of aeroplane frame or body, or other skeleton structure, comprising longitudinally extending chords, vertically disposed stanchions, the ends of which abut said chords, horizontally disposed stretchers, the ends of which abut said chords, yoke-bolts passing through the ends of said stanchions, each yoke-bolt having a shank-portion passing through the adjacent 100 end of one of said stretchers and a shank portion extending along one exterior side of said chords, a binder-plate connected with the ends of the shank-portions of each yoke-bolt and adapted to extend along another exterior side of said chords, nuts for securing said binder-plates in place, a plurality of 105 cross-ties or truss-connections, said yoke-bolts being provided with a projecting loop or anchor-portion adapted to retain the ends of said cross-ties or truss-connections, and a plurality of longitudinally extending ties or truss-connections extending diagonally from one yoke-bolt to another, substantially as and for the purposes set forth.

6. A construction of aeroplane frame or body, or other skeleton structure, comprising longitudinally extending chords, vertically disposed stanchions, the ends of which abut said chords, horizontally disposed stretchers the ends of which abut said chords, yoke-bolts passing through the ends of said stanchions, each yoke-bolt having a shank-portion passing through the adjacent end of one of said stretchers and a shank-portion 125 extending along one exterior side of said 130

- chords, a binder-plate connected with the ends of the shank-portions of each yoke-bolt and adapted to extend along another exterior side of said chords, nuts connected with said shank-portions for securing said binder-plate in place, each yoke-bolt further providing a loop or anchor-portion, cross-ties- or truss-connections extending from one loop or anchor-portion to another, 5
- 10 longitudinally extending ties or truss-connections extending from one yoke-bolt to another, said stanchions being provided with cutaway portions to permit the access of said ties or truss-connections to said yoke-bolts, 15 other longitudinally extending ties or truss-connections extending from a shank-portion of one yoke-bolt to a shank-portion of another yoke-bolt, said stretchers being provided with cutaway portions to permit the 20 access of said ties or truss-connections to said shank-portion, substantially as and for the purposes set forth.
7. A construction of aeroplane frame or body, or other skeleton structure, comprising longitudinally extending chords, vertically disposed stanchions, the ends of which abut said chords, horizontally disposed stretchers the ends of which abut said chords, yoke-bolts passing through the ends 25 of said stanchions, each yoke-bolt having a shank-portion passing through the adjacent end of one of said stretchers and a shank-portion extending along one exterior side of said chords, a binder-plate connected 30 with the ends of the shank-portions of each yoke-bolt and adapted to extend along another exterior side of said chords, nuts connected with said shank-portions for securing said binder-plate in place, each yoke-bolt 35 further providing a loop or anchor-portion, cross ties or truss-connections extending from one loop or anchor-portion to another, longitudinally extending ties or truss-connections extending from one yoke-bolt to another, 40 said stanchions being provided with cut-away portions to permit the access of said ties or truss-connections to said yoke-bolts, other longitudinally extending ties or truss-connections extending from a shank-portion 45 of one yoke-bolt to a shank-portion of another yoke-bolt, said stretchers being provided with cut-away portions to permit the access of said ties or truss-connections to said shank-portions, said ties or truss-connections each comprising an anchor-plate provided at each end with eye-portions, a tie-rod connected with one end of said anchor-plate, a stirrup-member, a nipple carried by said stirrup-member, adapted to receive and retain the other end 50 of said tie-rod, and a tail-piece provided with an eye-portion connected with said stirrup-member, substantially as and for the purposes set forth.
8. A construction of aeroplane frames or bodies, or other skeleton structures, comprising chords, vertically disposed stanchions, horizontally disposed stretchers, yoke-bolts surrounding said chords and connecting the ends of said stanchions and stretchers therewith, binder-plates for retaining said yoke-bolts in their holding positions, and a tying means extending diagonally from one yoke-bolt to another comprising ties or truss-connections, said ties or truss-connections each comprising an anchor-plate provided at each end with eye-portions, a tie-rod connected with one end of said anchor-plate, a stirrup-member, a nipple carried by said stirrup-member, adapted to receive and retain the other end of said tie-rod, and a tail-piece provided with an eye-portion connected with said stirrup-member, substantially as and for the purposes set forth.
9. A construction of aeroplane frames or bodies, or other skeleton structures, comprising chords, vertically disposed stanchions between said chords, horizontally disposed stretchers between said chords, yoke-bolts, a portion of each yoke-bolt passing through adjacent ends of a stanchion and a stretcher as the same abut a chord, and a portion of each yoke-bolt extending along the exterior of said chords, a binder-plate connected with each yoke-bolt, nuts for securing said binder-plates in place, and a tying means extending diagonally from one yoke-bolt to another comprising ties or truss-connections, said ties or truss-connections each comprising an anchor-plate provided at each end with eye-portions, a tie-rod connected with one end of said anchor-plate, a stirrup-member, a nipple carried by said stirrup-member, adapted to receive and retain the other end of said tie-rod, and a tail-piece provided with an eye-portion connected with said stirrup-member, substantially as and for the purposes set forth.
10. A construction of aeroplane frame or body, or other skeleton structure, comprising longitudinally extending chords, vertically disposed stanchions, the ends of which abut said chords, horizontally disposed stretchers, the ends of which abut said chords, yoke-bolts passing through the ends of said stanchions, each yoke-bolt having a shank-portion passing through the adjacent end of one of said stretchers and a shank-portion extending along one exterior side of said chords, a binder-plate connected with the ends of the shank-portions of each yoke-bolt and adapted to extend along another exterior side of said chords, nuts for securing said binder-plates in place, and a plurality of ties or truss-connections extending diagonally from one yoke-bolt to another, said ties or truss-connections each comprising an anchor-plate provided at each end with eye-portions, a tie-rod connected with one end of said anchor-plate, a stirrup-member, a nipple carried by said stirrup-member, adapted to receive and retain the other end of said tie-rod, and a tail-piece provided with an eye-portion connected with said stirrup-member, substantially as and for the purposes set forth.

ber, a nipple carried by said stirrup-member, adapted to receive and retain the other end of said tie-rod, and a tail-piece provided with an eye-portion connected with said stirrup-member, substantially as and for the purposes set forth.

In testimony, that I claim the invention

set forth above I have hereunto set my hand this 27th day of January, 1911.

GEORGE RIFFLARD.
